APPARATUS FOR TAPPING SHEET METAL

John H. Parsons, Pontiac, and Robert M. Powell,
Detroit, Mich.

Application November 13, 1936, Serial No. 110,572

7 Claims. (Cl. 153—2)

This invention relates to processes of and apparatus for tapping sheet material, in a novel manner involving bodily distortion of the stock, and aims to provide, in such materials as sheet metal, a threaded opening so formed as to hold firmly a tap bolt, stud, or the like, regardless of the pitch of its thread, under conditions in which the lead of the screw exceeds the thickness of the metal. A further object of the invention is the provision of means for automatically providing such opening with an edge bodily displaced to one side of the plane of the sheet, and lying upon an approximate helix, as well as provided with an edge bent to present one corner for engagement with the thread as the screw enters, so that if necessary the pitch of the helix may be modified by the bolt itself to correspond to the thread of the latter.

Another important object is the provision of improved combined punching, shearing, and forming means, adapted for use in conjunction with a punch press of conventional construction, and arranged to punch, shear, and form the sheet metal in the manner described in a single operation.

A further object is the provision of such improved combined punching, shearing, and forming means so constructed as to form in sheet material an opening having an edge of screw-threaded configuration and of novel and improved character, adapted to provide a better thread, calculated to more firmly hold the screw, and so shaped as to give the helical edge of the formed sheet metal a tendency to flow inwardly and grip the shank of a screw when tightened into place, thereby providing a self-locking action strongly resistant to escape or loosening of the screw.

Other objects and advantages will be apparent from the following description, wherein reference is made to the accompanying drawing illustrating a preferred embodiment of our invention and wherein similar reference numerals designate similar parts throughout the several views.

In the drawing:

Figures 1 and 2 show in perspective and in plan respectively a fragment of sheet metal provided with a helical-edge opening formed by the apparatus, and in accordance with the principles, disclosed herein.

Figure 3 is a perspective view of the male element.

Figure 4 is a perspective view of the female element.

55

Figure 5 is a side elevational view of the elements in operative relation, showing the tool supporting means for the male element partly broken away and in section.

Figure 6 is a view similar to Figure 5, but upon an enlarged scale, of the interacting parts of the elements, shown in the act of performing their work upon the sheet stock, the female element being partly broken away.

Figure 7 is a similar view of the parts in the act of performing their operation upon the work, taken at right angles to Figure 6, and substantially on the line 7—7 thereof, looking in the direction of the arrows.

Figure 8 is a plan view of the female element.

Figure 9 is an end view of the male element.

Figure 10 is a perspective view of a fragment of sheet stock provided with the completed threaded opening, showing a screw inserted and held therein, but not locked in place.

Figure 11 is a fragmentary side elevational view of a male element of somewhat modified construction.

Referring now to the drawing, in which Figures 1 and 2 illustrate the desired form of the finished threaded opening in the sheet metal, it will be seen that a central aperture 11 is provided having a helical edge which, commencing substantially in the plane of the sheet and at one side of a radially sheared line 12, rises uniformly about the circumference of the opening to its highest point at the opposite side of the sheared line, thus providing lower and upper lips 13—14 for ready engagement with the thread of the entering screw. The metal joining the upwardly projected helical edge to the flat body of the sheet is curved about a short radius, the metal thus forming a conoidal rather than a conic section. In order to punch and form the metal in the manner described, we provide combined punching, shearing, and forming means the construction of which is best shown in Figures 3 to 9 inclusive.

The members for performing the indicated operations comprise male and female elements 20—22 respectively, adapted to be supported in aligned relation for movement into and out of operative engagement, as one by the ram and the other by the bed of a punch press or the like (not shown). For purposes of description, it will be assumed that the male member is to be mounted in the ram and the female element in the bed of the press. The male member, to the shank of which is applied the general reference character 20, carries a punching stem 25 projecting down-

wardly from a flat land 30, and a shearing and forming blade 33 extends in inclined position from the periphery of the shank, at the land, to a point on the punching stem spaced from its 5 end. The shearing side of the angular blade comprises a flat surface which is extended longitudinally into the shank of the male member, as by cutting out the shank, in the manner indicated at 35, to provide a continuous flat surface 10 from the angular cutting edge of the blade to a point well up the shank.

The female element is provided with a die opening 24 adapted to receive the punching stem. A depressed central area 26 surrounds the opening 24. Projecting into abutting relation to the opening 24 is a substantially sector-shaped raised portion 28 having a flat, vertical, and radially disposed side wall 31 forming a shearing edge and aligned with the side of blade 33 which faces 15 the opening 35. A slot 29 joins the depressed central area and the exterior to form such cutting edge. Upon its other side, which extends substantially tangentially to the die opening and is also formed by a slot 32 joining the depressed 20 central area with the periphery, the edge of land 28 is curved downwardly, as indicated at 27, to allow the downward bending of the metal necessary in the area surrounding the aperture 11 to impart the desired conoidal configuration.

30 Although the land 28 extends to a point adjacent the die opening 24, the remainder of the upstanding marginal portion 36 of the female member, surrounding the depressed area, is spaced outwardly from the opening, allowing the 35 metal surrounding the punched-out central opening 11 of the work to bend downwardly in the desired curvature, the extent to which it is bent being governed not merely by the shape of the male member, the angularity and thickness of the blade 33, but by the extent to which the male member is forced downwardly. By adjusting the 40 travel of the press ram, therefore, the extent to which the lip 14 is pressed out of the plane of the remainder of the sheet, and so the pitch of the helix, may be varied, although it will be 45 seen to be always necessary to press such lip entirely out of overlapping relation with respect to lip 13, in order that a free edge may be presented to the entering screw.

50 Descent of the punch, after cutting out the central area, carries the web 33 into engagement with the cutting edge 31 of land 28, to cut the radial sheared line. Due to the fact that the central depressed area of the die is substantially larger than the perforation, the work, 55 except that portion overlying the land 28, is supported only upon this circular area spaced from the punch opening, allowing the metal to be carried downward and to bend naturally in a curved line. The area which forms the lower lip is supported by the land 28, and so maintained substantially in the plane of the sheet. The curvature at the point designated 27 allows the gradual bending of the work from the low point at lip 60 13, toward the remainder of the helix, from the flat area overlying the land 28 to the section bent farthest out of plane by the web 33.

The functioning of the web 33 is best shown in Figures 6 and 7. As there indicated, after formation of the cut by its edge which bounds the opening 35, the opposite top corner of the web presses downwardly upon the metal at a point spaced from the line of shear, acting to bend the metal about a curved line, and by a multiplying 65 action forcing the edge downwardly farther than 70

the blade extends, and imparting the desired curvature to the portion of the metal extending to the higher lip (the frusto-conoid being formed in inverted position).

It is of course important that the elements be held in rigid alignment and locked against rotation with respect to one another. For this purpose the shank 20 is shown held in the ram of the press by means of a retainer mechanism corresponding to that disclosed in the copending application of John H. Parsons et al., Serial No. 640,466, filed October 31, 1932 (Patent No. 2,107,581, granted February 8, 1938). The retainer comprises a block 40, apertured as at 41 to receive the shank and provided in its top face with a transverse channel 43 intersecting the bore 41, while a detent member 45 slidable in the transverse opening into and out of the tool socket 41 is engageable with a slot as 46 cut in the tool shank for locking engagement therewith. The 10 detent member 45 is actuatable by a wedge cam 46 connected to an operating plunger 47 projecting downwardly through the block and from the under side thereof for convenient manipulation, a spring as 48 normally holding the wedge cam 15 member in such position as to urge the detent into the tool socket, and so lock the tool in place, while when the plunger member 47 is pressed upwardly and the wedge member released, the 20 shank may easily be inserted and removed. The 25 detent 45 extends transversely along a chord of the cylindrical tool socket, and the slot in the tool shank similarly extends transversely, whereby the detent holds the shank against turning. The 30 top of the slot in the tool shank will also be 35 seen to be so inclined that urging of the detent inwardly by the spring 48 also tends to force the shank into the tool socket.

Figure 10 shows a screw inserted in the formed opening, and it will be apparent that, provided 40 only the threads be stiffer than the metal, further tightening of the screw after its complete insertion to the extent there shown will result in drawing the raised portions and lip 14 downward toward the plane of the sheet, flattening it against 45 the backing provided by the head of the screw or other work attached to the face of the sheet metal. Such flattening also forces the helical edge into the root of the thread and against the shank of the screw, the action being assisted by 50 the excess metal provided by, and the shape of, 55 the conoidal surface.

As indicated in Figure 11 at 33A, the cutting edge of the shearing and forming blade may be curved about a transverse axis to change, for a 55 given ram travel, the relative proportion of the length of the sheared line to the distance the high corner is thrown out of plane. It will be seen that these factors may be accurately controlled by varying the curvature of the blade in 60 this respect.

While it will be apparent that the illustrated embodiments of our invention herein disclosed are well calculated to adequately fulfill the objects and advantages primarily stated, it is to be understood that the invention is susceptible to variation, modification and change within the spirit and scope of the subjoined claims.

What we claim is:

1. Means for punching, shearing and forming 70 sheet material to impart a desired configuration thereto, comprising cooperating male and female members, the former having a punch portion and a shearing blade of substantial but definitely limited thickness intersecting and extending outward- 75

- ly from the punch portion, the female member having a substantially flat work-backing rim, a die opening adapted to receive such punch portion and a countersunk area extending partly around the die opening between such die opening and the rim, a substantially flat and segmental land substantially co-planar with the rim of the female member and extending inwardly to the die opening, said land having a cooperating shearing edge positioned in operative alignment with one face of the shearing blade, said rim having a circumferentially extending cut out area substantially wider than the thickness of the shearing blade, into and from which the blade is reciprocable, one side of the cut out portion being defined by said shearing edge, whereby excess free bending of the work due to the thickness of the blade may occur in said cut out area without obstruction by the female member.
5. Means as set forth in claim 1 in which toward its outer extremity said shearing portion of the male member is inclined backwardly with respect to the direction of projection of the punch portion.
10. Means as set forth in claim 1 in which the portion of the male member overlying said land
15. Means as set forth in claim 1 in which the portion of the male member overlying said land
20. Means as set forth in claim 1 in which the portion of the male member overlying said land
25. Means as set forth in claim 1 in which the portion of the male member overlying said land

is relieved to prevent engagement between the male member and the work above the land.

4. Means as set forth in claim 1 in which the portion of the male member overlying said land is relieved to prevent engagement between the male member and the work above the land, said male member also having outwardly extending portions overlapping the rim.

5. Means as set forth in claim 1 in which the male member extends outwardly and overlaps the rim.

10. Means as set forth in claim 1 in which the portion of the male member overlying said land is relieved to prevent engagement between the male member and the work above the land, said male member also having outwardly extending portions overlapping the rim and substantially flat and parallel to the rim.

15. Means as set forth in claim 1 in which toward its outer extremity said shearing portion of the male member is curved longitudinally and extends backwardly with respect to the direction of projection of the punch portion.

20. JOHN H. PARSONS. 25
ROBERT M. POWELL.
